BY

Arthur B. Jenkins,
ATTORNEY.

UNITED STATES PATENT OFFICE.

OWEN H. JONES, OF HARTFORD, CONNECTICUT.

BALL-COCK.

1,312,329.

Specification of Letters Patent.

Patented Aug. 5, 1919.

Application filed March 1, 1919. Serial No. 280,052.

To all whom it may concern:

Be it known that I, OWEN H. JONES, a citizen of the United States, residing in Hartford, in the county of Hartford and State of Connecticut, have invented a new and Improved Ball-Cock, of which the following is a specification.

My invention relates to the class of devices employed for automatically controlling flow of liquid to a receptacle, and an object of my invention, among others, is to provide a device of this class that shall be particularly efficient in its operation and that shall prevent objectionable escape of liquid during the operation of the device.

One form of device embodying my invention and in the construction and use of which the objects herein set out, as well as others, may be attained, is illustrated in the accompanying drawings, in which—

Figure 1 is a view in elevation of a ball cock embodying my invention with parts cut away to show construction.

Fig. 2 is a view in elevation of my improved device viewed from a point located at right angles to the point of view of Fig. 1.

Fig. 3 is a side view of the hood.

Fig. 4 is a bottom view of the same.

In the use of ball cocks, and especially those employed to control supply of liquid to a tank or receptacle, it is desirable that the plunger 5 shall loosely fit within the neck 6 of the valve case 7, this in order that small pieces of sand or dirt that may be present in the liquid will not obstruct free movement of the plunger in its operation by a float on the float rod 8. In making the plunger loose for this purpose, however, another and serious fault is encountered in that liquid will be forcibly ejected from the top of the neck 6 and out at the top of the tank, and it is to obviate this objectionable result that I have devised means for preventing spouting of the liquid out of the tank, flow to which is controlled by my improved ball cock.

The improved device herein shown for accomplishing this result consists of a hood 9, formed to removably fit the end of the neck of a ball cock of common construction, said hood having a lug 10 projecting from its interior surface near the bottom edge in position to rest upon the end of the neck 6, the opening through the bottom of the hood being of a size and shape preferably to leave

an opening between the hood and the neck, or a flange 11 thereon. Lugs 12 project inwardly from opposite side parts 13 of the hood, at the bottom to bear against the edge of the neck or a flange thereon, said hood 60 being open at the front as well as at the bottom. The sides 13 of the hood are spaced apart sufficiently to receive ears 14, between which the float rod 8 is pivoted, a pin 15 supporting said rod extending through the 65 sides 13 to removably secure the hood in place. A rib 17 is formed on the upper wall of the hood to prevent the liquid from spouting out through the opening at the front of the hood, and liquid escaping along the 70 plunger into the hood may freely pass out at the opening 16 at the bottom of the hood, whenever the liquid lowers sufficiently within the tank to permit this.

In accordance with the provisions of the 75 patent statutes, I have described the principles of operation of my invention together with the device which I now consider to represent the best embodiment thereof; but I desire to have it understood that the device 80 shown is only illustrative and that the invention may be carried out by other means.

I claim—

1. A ball cock including a case, a plunger projecting through one wall thereof, a float 85 rod supported by said case, and a hood secured to the end of the case and overlying the end of said plunger to obstruct spouting of liquid from said case and means for retaining said hood in place. 90

2. A ball cock including a case, a plunger projecting through one wall thereof, a float rod, a hood to overlie the end of said plunger to obstruct spouting of liquid from the case, and a pivot pin pivotally securing said 95 rod on the case and removably securing said hood in place.

3. A ball cock including a case, a plunger projecting through one wall thereof, a hood secured to the end of the case and overlying 100 the end of said plunger, lugs projecting from the inner side of the hood to support it in position on the case, and means for removably securing the hood in place.

4. A ball cock including a case, a plunger 105 projecting through one wall thereof, a hood secured to the end of the case and overlying the end of said plunger, a lug projecting from the inner side of the hood to support it against vertical movement, a lug project- 110

ing from said hood to support it against horizontal movement, and means for removably securing the hood in place.

5. A ball cock including a case, a plunger projecting through one wall thereof, a hood removably secured to the end of the case and overlying the end of said plunger to obstruct spouting of liquid from said case, and a rib at the top of the hood on its inner 10 side to obstruct spouting of water from said hood.

6. A ball cock including a case, a plunger projecting through one wall thereof, a hood having walls surrounding the end of the

case and spaced therefrom, a lug to support 15 the hood against vertical movement, a lug to support it against horizontal movement, and means for removably securing the hood in place.

7. A ball cock including a case, a plunger 20 projecting through one wall thereof, a hood secured to the end of the case and overlying the end of said plunger, projecting lugs positioned to support the hood and retain it in position on the case, and means for removably securing the hood in place.

OWEN H. JONES.
